UNITED STATES PATENT OFFICE

ERNEST ASHLEMAN, OF WICHITA, KANSAS

ADJUSTABLE CHAIR

Application filed October 14, 1931. Serial No. 568,666.

My invention relates to an adjustable chair.

The object of my invention is to provide a chair that is adjustable with respect to the back and collapsible to a compact position for storage, shipping or the like.

A still further object of my invention is to provide an adjustable foot rest for the chair detachably arranged.

10 A still further object of my invention is to provide a chair that may be adjusted by the occupant while seated therein and also the foot rest thereof.

15 A still further object of my invention is to provide a chair that the back and foot rest will adjust sufficient to function as a couch or the like.

20 A still further object of my invention is to provide a chair adaptable for use in hospitals or the like, the said chair to be provided with rollers.

These and other objects will herein be more fully explained, reference being had to the accompanying drawings forming a 25 part of this specification in which like characters will apply to like parts in the different views, and in which:

Fig. 1 is a side view of the chair positioned for the normal seating posture.

30 Fig. 2 is a rear view of the chair.

Fig. 3 is a vertical section thru the chair.

Fig. 4 is a side view of the chair collapsed for storage or transportation.

35 Fig. 5 is a side view of the foot rest with the chair fragmentarily shown.

Fig. 6 is a side view of the foot rest aligned with the plane of the chair, the chair fragmentarily shown.

40 Fig. 7 is a plan view of the foot rest as shown in Fig. 6 with the chair removed.

My invention herein disclosed is a collapsible chair and foot rest combined consisting in detail of side rails 1 rearwardly extending and slanting downward as rear legs 45 for the chair; attached to the upper edges thereof and connecting the same is a plurality of slats 2 spaced apart functioning as a seat, the said rails are pivotally connected to the front legs 3 by a rod 4 extending 50 from one to the other, the said legs are

further braced by a bar 5 positioned in close proximity to the lower ends thereof, and a second bar 6 spaced downward from the front slat of the seat communicating with the ends of rails 1 and between the bars 65 the legs of the foot rest will engage as later described.

To the upper end of the front legs are pivotally connected an arm element 7 as at A, the rear end of the said arms being carried by a rod 8 extending across the back of the chair and trunnioned thereon thru the medium of bearings 9 that are secured to their respective slats 10 of the back; the said slats being connected by a cross bar 11 spaced downward from the upper ends thereof, the lower ends being connected by a rod 12 that pivotally engages on the side rails 1 from which point the back may be rocked to a desired angle rearward thru the medium of a pair of standards 13, the upper ends of which engage on the said rod 8 while the lower ends are rigidly carried by another rod 14, the last said rod pivotally engaged at each end by an arm 15 that is secured to a shaft 16 rotatably arranged and trunnioned at its outer ends on the side rails 1 near the rear extremities thereof, the said rod being rotated by a crank 17 by which means a reciprocating movement is imparted to the standards 13 carrying with them the back of the chair to a desired angle rearward, the arms 7 are likewise drawn rearward, causing the front legs to rock simultaneous with the movement.

To overcome excess friction that would occur by the rocking movement of the front legs, I have secured to the lower end of each, a roller 18 and to the rear end of rails 1 a castor 19, the latter being the means to turn the chair while moving the same from place to place.

In Fig. 3 is shown a rearward slant of the back greater than that shown in Fig. 1 which is accomplished by a rearward rock of lever 17 as shown by dotted lines B in Fig. 1 showing the extreme downward movement of the standard 13, carrying the back therewith.

To nearly align the back with the seat as

shown by dotted lines C in Fig. 3, I have provided a slot 20 longitudinally in each of the standards in which the rod 14 will slidably engage; to avoid sliding engagement, a stop 21 is positioned in the slot, the lower end of which will have its bearings on said rod, the upper end of the slot being hinged to the standard as at 22 by which means the said stop may be rocked outward to clear the slot of obstruction when the downward position of the back is desired.

In Fig. 3 is shown a disk element 23 having an arm 24 tangentially extending therefrom, the disk is trunnioned on shaft 16 adjacent the inside of side rails 1, the arms of the disks slidably engage in a notch positioned in each end of a cross rail 25 that is carried by the said side rails. To avoid the upward movement of the arms, a pin 26 is firmly affixed to their respective rails, by which means the said disc is retained against rotation but free to move longitudinally when shaft 16 is moved upward in slot 27, the latter movement being required when the chair is folded as shown in Fig. 4, in which operation the ends of the rods 12 will be guided rearward in their respective slots 28, by which means the back will rock forward resting on the seat while the legs 3 and their respective arms 7 will fold simultaneously therewith, all of which will be in parallelism and in close proximity to the side rails as shown in Fig. 4.

Radially extending from the said disk 23 and integral therewith is a shoulder 28' as shown in Fig. 3, and on which the outer end extensions of rod 14 will rest supporting one angular position of the back while another position is supported by seating the said end portions in depressions 29 formed in the peripheral edges of the disks by which means rotation of the shaft 16 is prevented when pressure rearwardly is imposed on the said back.

When the ends of the rod 14 seat as above described, radial movement thereof is required with respect to the disk and to permit such movement a slot 30 is arranged in each arm in which the ends of said rod 14 will slidably engage but is restricted against inward movement by reason of engagement on the periphery of the disk as driven therearound by the crank 17 which imparts rotation to shaft 16.

In Figs. 5, 6, and 7 is shown a foot rest for the chair attachable and adjustable in its connection with the chair and also adjustable to accommodate for the desired position of the occupant.

The component parts thereof consist of a pair of arms 31 connected at the rear ends by a cleat 32, the said cleat having a lip D upwardly extending to snuggly engage between the slats of the chair bottom avoiding longitudinal movement thereof while

the arms cantilever on bar 6 as carrying means for the outer portion of the structure. Rockably arranged and pendants carried by the arms is a platform 33 on which to rest the feet of the occupant while seated in the chair.

The pendant supporting means consists of a pair of hangers 34 to carry the rear portion of the platform each having a slot 35 extending a short distance from the lower ends thereof and in said slot a pin is secured to each side of the platform as carrying means therefor, the other ends of said hangers are pivoted by pins 36 carried by the said arms 31; the front portion of the platform is pendants carried by a slotted hanger 37 that links the same to the outer ends of the said arms by engaging with headed pins 38 and rod 39.

Positioned on each of the hangers 37, is an extension 40 having on the upper end of each a slot 41 to engage pins 36 when the foot rest is elevated as shown in Fig. 6.

The manipulating means of each hanger 37 is thru the medium of a knob 42 positioned in close proximity to the base of the slots 41 respectively.

It is understood that the platform is rockable to the position shown by dotted lines in Fig. 6; the slotted features of hangers 34 and 37 are to accommodate for sliding movement of the several pins and rod as the platform is rocked or elevated as shown in the different views.

Having fully described my invention what I hope is new and desire to secure by Letters Patent is:

1. In an adjustable chair of the class described comprising a pair of side rails and front legs pivotally carrying the front ends of the rails, the side rails having a seat arranged thereon the side rails carried by the front legs and rearwardly extending, a back pivotally mounted on the side rails, and an arm pivotally connecting the upper end of each front leg to its respective side of the back, a shaft trunnioned and carried by the rear ends of the side rails, and a crank thereon to rotate the same, arms secured to the shaft and rockable therewith, standards pivotally connecting the free ends of the arms with the back as rocking means therefor when the shaft is rotated.

2. In a chair of the class described comprising a pair of front legs, and a pair of side rails, the forward ends of which are pivotally carried by the legs respectively, each side rail having a slot longitudinally extending in parallelism therewith, and also having a second slot rearwardly positioned from the first said slot, the last said slot having an oblique upward turn, a back and a rod transversely crossing the lower end of the back, the outer ends of the rod engaging in the first said slots respectively, and

an arm pivotally connecting each front leg with the back, a shaft trunnioned in each of the last said slots respectively, and a crank thereon to turn the same, a disc carried by each end of the shaft adjacent the inside of its respective side rail, each disc having an arm and guiding means therefor when the shaft is moved longitudinally in the slots, each disc having a plurality of 10 seats arranged in the periphery thereof, a rod and arms secured to the shaft carrying the said rod while the outer ends thereof slidably engage on their respective discs, standards connecting the rod to the back as 15 slanting and supporting means therefor, the slots being for the displacement of the elements carried therein when the chair is collapsed to a folded position.

3. In a chair of the class described comprising a pair of front legs and rearwardly inclined side rails functioning as rear legs, the forward ends of which are pivotally carried by the said front legs, a back and seat carried by the side rails, the back pivotally arranged thereon, and an arm pivotally connecting the upper end of each leg to the back, a pair of slotted standards pivotally attached at one end to the back axially aligned with the pivot connection of the arm thereto, a rockably arranged rod carrying the other end of the standards, the rod engaging in the slots therein and means to rock the rod, a removable stop in the slot of each standard holding the rod therein.

ERNEST ASHLEMAN.
